UNITED STATES PATENT OFFICE.

PERLEY R. GLASS, OF BROOKLINE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

COMBINED SOLE LAYING AND NAILING MACHINE.

1,325,085.

Specification of Letters Patent. Patented Dec. 16, 1919.

Original application filed December 22, 1913, Serial No. 808,183. Divided and this application filed August 15, 1916. Serial No. 114,985.

To all whom it may concern:

Be it known that I, PERLEY R. GLASS, a citizen of the United States, residing at Brookline, in the county of Norfolk and State of Massachusetts, have invented certain Improvements in Combined Sole Laying and Nailing Machines, of which the following description, in connection with the accompanying drawings, is a specification, like reference characters on the drawings indicating like parts in the several figures.

The present invention relates to machines for operating upon shoes and particularly to machines for operating upon the soles of boots and shoes. The invention is herein shown by way of illustration as embodied in a fastening inserting machine of the type shown and described in my co-pending application Serial No. 808,183, filed December 22, 1913, and issued November 20, 1917 as Patent No. 1,246,906, of which application the present application is a division.

In the manufacture of boots and shoes, it is the usual practice first to lay the outsole upon the shoe bottom and then to attach the heel end of the outsole to the insole and upper by nails before the sole is secured to the shoe about the forepart. Heretofore the sole laying operation and the heel seat nailing operation have been performed by independent machines each of which required to be operated separately. This manner of laying and attaching the sole to the shoe not only requires considerable skill and care on the part of each operator to obtain uniformity but it frequently happens that in transferring the shoes from one machine to the other the soles become displaced so that they are not secured in their proper locations.

One of the objects of the present invention is to provide in one machine an organization whereby an operator may lay an outsole upon the bottom of a shoe and quickly and accurately attach the heel end of the outsole to the insole and upper of the shoe by means of nails or other metallic fastenings.

To this end, the illustrated machine comprises mechanism for attaching the heel seat end of an outsole to a shoe together with mechanism for laying the sole on the shoe

bottom, which last-named mechanism is constructed and arranged to lay the heel seat end of the sole and the forepart of the sole separately, the heel seat end of the sole being laid prior to the insertion of the heel seat attaching fastenings. In the embodiment of the invention shown herein the machine is so constructed and arranged that, if desired, the means for laying the forepart of the sole may be held out of operation until the laying of the heel seat end of the sole has been completed.

Another object of the invention is to provide means for laying an outsole, the construction preferably being such that the laying of both the forepart and the heel part of the sole are under the control of the operative. In the illustrative construction, the forepart sole laying means may be operated either manually or through power means under the control of the operative. Conveniently the laying of the forepart of the sole may take place either before or after the laying and attaching of the heel end of the sole.

These and other features and objects of the present invention are explained more fully in the following detailed description, which is to be read in connection with the accompanying drawings, and are set forth in the appended claims.

In the drawings,—

Figure 1 is a side elevation of a machine having a preferred embodiment of the present invention incorporated therein;

Fig. 2 is a left hand side elevation of the upper part of the machine shown in Fig. 1;

Fig. 3 is a detail in perspective showing the sole laying mechanism and a part of its operating mechanism;

Fig. 4 is a longitudinal section along the main driving shaft showing the construction of the various clutches and the operating mechanism;

Fig. 5 is an enlarged detail in perspective showing the operating mechanism for the sole laying mechanism and the connections between this mechanism and the fastening inserting mechanism; and

Fig. 6 is a detail in elevation of a part of the mechanism shown in Fig. 5.

The illustrated machine is like that dis-

closed in my above mentioned co-pending application Serial No. 808,183. Accordingly, only so much of the machine will be described in detail herein as is necessary to 5 a clear understanding of this invention and reference may be had to said co-pending application for a description of features of construction not fully described herein.

The nails which attach the heel seat are 10 preferably driven simultaneously and in order that the machine may operate effectively upon shoes of a wide range of sizes and to provide for adjusting the nailing mechanism quickly and easily to accommodate different ranges of sizes of shoes, three gangs 15 of nail drivers are provided, each gang being intended for use on five different sizes of shoes. These gangs of drivers, each composed of a number of drivers 50 corresponding 20 to the number of nails it is desired to insert in the heel seat to secure it firmly in position, have dovetailed connections with the lower end of a driver operating plunger 28 which is reciprocated in a movable casing 46 through a rack 30, segment gear 32, and levers 36, 38 connected to a cam disk 42 upon a driving shaft 43. The lower portion 25 of the plunger 28 is somewhat smaller in one of its transverse dimensions so that it may enter one of the guides in a driver guide slide arranged to slide transversely 30 through the casing 46 to bring the selected gang of drivers into operative position.

The awls 60, of which there are three 35 gangs corresponding in numbers and arrangement to the three gangs of drivers, are carried by an awl carrying slide 74 and automatic means is provided for moving the slide to cause it to bring the selected gang of 40 awls into operative position in the lower part of the casing 46. This means comprises a pusher bar having a vertical dovetail connection with the awl carrying slide 74 at its front end to provide for the vertical reciprocation of the awls and connected 45 at its rear end to a cam disk upon the driving shaft 43.

The nails to be driven are delivered into suitable openings in a nail block 100 through 50 which they pass into contact with the work and into which the drivers enter to drive the nails. The nail block is provided with three sets of nail receiving openings which correspond in numbers and arrangement to the 55 three sets of drivers and awls, the nail block being constructed and arranged to be moved into positions to bring the desired openings into operative relation to the corresponding gangs of drivers and awls.

60 The nails are delivered to the openings in the nail block 100 by nail loaders 162, there being one of these nail loaders for each of the three size ranges so that the openings in the nail loader will register properly with

the openings in the nail block and each nail 65 loader is adapted to be slipped into the nail loader carrier when the nail block has been adjusted to bring the set of nail receiving openings for that size range into proper position beneath the nail loader carrier. The 70 nail loader has a rib and groove connection with the awl carrying slide 74 which permits the slide 74 to reciprocate and also enables the nail loader to be moved between nail receiving position and nail delivering position 75 by the movement of the awl carrying slide into and out of operative position.

The nail block, the awls and the drivers are moved into operative relation to each other by a hand lever 110 connected through 80 a rack and gear connection 114 to the driver guide slide to bring the gangs of drivers into operative relation to the plunger 28, to the awl carrying plates, and to the nail block to move it into position beneath the proper 85 gang of drivers intended to enter the openings.

The means for supplying nails to the nail loader when it is in fastening receiving position comprises a plurality of flexible nail 90 tubes 168, one for each opening in the nail loader, these tubes serving to guide the nails from a corresponding number of raceways which are supplied with nails by segmental lifting plates 286. These lifting plates oscillate in a nail pot or holder 288, the plates being carried upon a rock shaft 294 which has connections to a shaft 310 connected to the source of power so that the nail supplying mechanism may be constantly operated. 95 A nail separator is provided to deliver the nails from the raceways to the nail delivering tubes 268.

Any suitable work support may be used 100 with this machine. In most instances, however, a work support of the jack type will be preferred since the heel seat is preferably nailed while the shoe is upon an iron bottom last which acts to clench the nails upon the inside of the shoe. The illustrated 105 jack is of the type in which the shoe is supported both at the toe and heel ends and comprises a toe post 648 carrying a toe pad 652 and a heel post 646 carrying a last pin (not shown) both posts being mounted upon 110 a bed 644. This bed is slidably carried upon a bracket 658 pivotally secured to the upper end of a work supporting post 641 which is movable toward and from the machine on a 115 rock shaft 642 in the base of the machine 120 frame.

In accordance with the present invention, the illustrated machine is organized to lay the outsole on the shoe bottom and to nail the heel seat end of the outsole to the shoe 125 bottom, the heel seat end of the outsole being laid independently of the forepart of the outsole and prior to the insertion of the nails

to secure the heel seat end of the outsole to the insole and upper. To this end, the under side of the nail block 100 at each set of nail receiving openings is shaped to conform substantially to the contour of the bottoms of the particular sizes of shoes it is to operate upon and is provided with a pad formed of suitable resilient material such as leather or rubber which serves as a blocking or pressing pad to engage the outsole. The shoe to be operated upon is mounted upon the work support and pressed up against the under side of the nail block 100 which has previously been selected for the particular size range whereby the heel seat end of the outsole is conformed to the shoe bottom and the outsole held accurately in position on the shoe to receive the nails.

The illustrated means for laying the fore-part of the sole comprises a carrier 386 for a sole pressing pad 388, this carrier being provided with trunnions 390 received in slots 392 in brackets 394 clamped upon vertical rods 396 extending from the head of the machine to the base. The rods 396 have other functions besides supporting these brackets, among which functions is that of strengthening and stiffening the frame of the machine so that it will resist the strains which come upon it during the nailing and sole laying operations.

In the illustrated embodiment of the machine the standard 10 carries a head 12 upon which are supported the nailing and sole laying mechanisms. The front part of the head overhangs the base portion of the standard in order to position the said mechanisms above and in line with the work on the work support extending up from the base portion of the standard. The whole frame including the standard and head is, therefore, approximately C-shaped. During the operations of nailing and sole laying great pressures are exerted downwardly on the work with the corresponding reactions against the arms 12^a and 12^b of the frame which carry the nailing and sole laying mechanisms and the operating mechanisms therefor. The forces thus applied to the work tend to separate further the overhanging part of the frame, i. e. the upper arm of the C-shaped frame, from the base of the standard or the lower arm of the C-shaped frame. In a machine frame of the ordinary weight and strength, these forces tending to further separate the arms of the C-shaped frame cause distortion of the frame and of the connected structures—distortion that may become serious enough to interfere with the proper operation of the machine. In order to overcome this tendency to distortion in the frame, tie rods 396 are employed which are fixedly secured at their lower ends to the foot of the standard by means indi-

cated at 396^a, and connected at their upper ends to the arm 12^a by pinned collars (Figs. 2 and 3) or by nuts threaded thereon (Fig. 4) above the bearings in the arm through which the rods pass. The tie rods are also fixedly secured to the arms 12^a by bolted clamps (Fig. 3), thus tying the two arms 12^a and 12^b together and preventing their springing apart during the operations referred to. It is obvious that other means than that shown may be employed for securing the tie rods to the head and standard of the machine.

Attached to the sides of the pad holder 386 at its rear are adjustable slotted arms 398 which receive within their slots headed studs 400 carried by the brackets 394. The arms 398 and the slots 392 in the brackets 394, serve to guide the pad holder during its downward movement and to cause it to turn from the position shown in Fig. 3 to the position shown in Fig. 1 in which latter position it is out of the operator's way and allows an unobstructed view during the laying of the sole at the heel seat end and the nailing of the heel seat. The movements of the pad holder 386 are controlled by connections with a crank disk 402 comprising adjustable links 404 pivoted at their lower ends upon the trunnions 390 and at their upper ends receiving pivot screws 406 threaded into adjustable sleeves 408 which are clamped upon rods 410 arranged to slide vertically in guides 412 upon the front of the machine frame. The rods 410 are connected at their upper ends to a cross-head 414, provided with a horizontal slot which receives a sliding block 416 upon the crank pin 418 of the crank disk 402.

The crank disk 402 is carried upon the front end of a horizontal shaft 420 which carries at its rear end a bevel gear 422. The shaft 420 is operated through a bevel pinion 424 upon an oblique shaft 426 which is connected by bevel gears 428, 430 to a horizontal shaft 432 extending at right angles to the shaft 420. A gear wheel 434 upon the horizontal shaft 432 is driven by a pinion 436 attached to a sleeve 438 upon the driving shaft 440. As shown, the sleeve 438 is clutched to a loose driving pulley 442 by a clutch mechanism hereinafter described. The gearing between the pulley 442 and the crank disk 402 is such that it takes two rotations of the pulley 442 to move the sole laying pad holder 386 into its operative sole laying position and two more rotations of the pulley 442 to restore it to its inoperative position.

The sole laying mechanism is so arranged that it may be operated either independently of or after an operation of the nailing mechanism. To this end, independent means are provided for clutching the nailing mecha-

nism and the sole laying mechanism to the driving pulley 442. The means for connecting the nailing mechanism to the driving pulley 442 comprises a cone clutch member 444 carried by a sleeve 446 arranged to slide longitudinally of the shaft 440 and relatively to a spider 448 rigidly connected to the shaft 440 and adapted to engage projections 450 on the inside of the clutch member. The conical clutching portion 452 of the clutch member 444 is preferably formed of some good friction material, such as cork, and is adapted to engage a conical surface 454 upon the inside of the pulley 442. The clutch member 444 is preferably provided also with a conical surface 456 formed of similar friction material adapted to engage corresponding surfaces upon a brake member 458 when the clutch is in its released position.

The clutch member 444 is normally held in clutching position by a spring 460 which surrounds the shaft 440 and bears at one end against a shoulder formed upon a ring 461 threaded upon the sleeve 446 and at its other end against a shoulder formed upon a second ring threaded upon another sleeve 462 rigidly attached to the shaft 440. The clutch member 444 is held out of clutching relation to the pulley 442 by means of a lever 464 fulcrumed at 466 upon the machine frame and forked at its upper end. Each of the fork members 468 of the lever 464 is provided with a slot 470 which receives a trunnion 472 upon a ring 474 arranged to turn upon the sleeve 446.

The lever 464 is provided with a laterally extending lug 476 which is normally engaged by a lug 478 upon a link 480 pivotally connected to the lower end of a lever 482 fulcrumed at 484 upon the machine frame. When the parts are in the positions shown in Fig. 4 the link 480 causes the lever 464 to hold the clutch member 444 out of clutching relation to the pulley 442. The link 480 is normally held in such position that the lug 478 will remain in engagement with the lug 476 by means of a spring-pressed plunger 486 which is normally maintained at the uppermost limit of its movement by a spring 488. The link 480 may be moved out of its operative clutch releasing relation to the lever 464 by connections to a treadle 490 in the base of the machine. These connections comprise a rod 492 pivotally connected at its lower end to the treadle 490 and having pivoted to its enlarged upper end 494 a hook or latch member 496, the hook portion 498 of which is adapted to engage a catch plate 500 attached to the side of the link 480 or formed integral with said link. This catch plate 500 extends slightly beyond the end of the link 480 and overlaps the lever 464 whereby it serves to guide the relative move-

ments of the link 480 and the lever 464. As the treadle is depressed, the hook 498 engages the catch plate 500 and moves the lug 478 out of engagement with the lug 476, thereby permitting the lever 464 to turn about its pivot 466, whereby the spring 460 is permitted to move the clutch member 444 into clutching relation to the pulley 442. As the lever 464 turns about its pivot 466 an adjustable stud 502 in the lower end of the lever 464 engages the boss 503 upon the latch member 496 and turns said latch member about its pivotal connection with the enlargement 494 of the rod 492 until the hook 498 is moved out of engagement with the catch plate 500, thereby permitting the link 480 to be restored to its normal position by the action of the spring-pressed plunger 486.

In order that the lug 478 may again come behind the lug 476 it is necessary that the link 480 be moved longitudinally toward one side of the machine. This movement of the link 480 is effected by means of a spring 504 but is only permitted when the shaft 440 has turned through a certain angle of rotation.

The means for determining the time of the clutch releasing movement of the lever 464 comprises a cam disk 506 mounted to turn freely upon the end of the shaft 440 and driven from said shaft through a train of gears 508, 510, 512 and 514, so that said cam disk makes one rotation for two rotations of the shaft 440. The cam disk 506 is provided with a face cam 516 against which bears a cam roll 518 upon the lever 482. When the low part of the face cam 516 comes beneath the cam roll 518, the link 480 is moved rearwardly by the spring 504 and thus the lug 478 is permitted to come behind the lug 476 so that when the high part of the cam 516 comes beneath the cam roll 518 the link 480 will turn the lever 464 about its pivot 466 in a direction to move the clutch member 444 out of clutching relation to the pulley 442.

When the shaft 440 is turned over by hand, unless provision is made for preventing movement of the clutch member 444 into engagement with the pulley 442, such movement will take place as the cam 516 turns until its low point comes beneath the cam roll 518. To prevent this clutching movement and thus permit the shaft to be turned over easily when the brake is removed by means hereinafter described, a stop 519 is arranged in the path of an adjustable stop 523 upon the lever 464, the stop 519 comprising a link pivoted at 525 upon the machine frame and held normally in the path of the stop 523 by a spring 527. When the rod 492 is drawn down to effect the clutching of the clutch member 444 to the pulley 442 the stop 519 is drawn out of the path of the stop 523.

by connections with the latch member 496 comprising a link 529.

- As already stated, the sole laying mechanism may be manually controlled, or it may be operated automatically after other operations upon the shoe have been completed. Preferably means is provided whereby the sole laying mechanism may either be manually actuated so that it will be brought into operative sole laying position before the nailing operation begins and then will be automatically moved out of operative position after the nailing operation is completed, or it may be automatically brought into operative sole laying position after the nailing operation is completed and then may be manually actuated to bring it into inoperative position after the sole has been allowed to set to shape.
- 20 The means for connecting the gear 436 to the driving pulley 442 comprises a clutch member 526 carried by a sleeve 528 arranged to slide longitudinally of the shaft 440 upon the sleeve 438. The clutch member 526 has a conical clutching surface formed of suitable friction material 530 which is arranged to engage a co-operating conical surface 532 upon the inside of the pulley 442. A spider 534, rigidly connected to the sleeve 438, is adapted to engage projections 536 upon the inside of the clutch member 526. A spring 538, confined between a ring 540 threaded upon the sleeve 528 and a second ring threaded upon a sleeved extension of the gear 436, tends to move the clutch member 526 normally into clutching relation to the pulley 442. The clutch member 526 is normally held out of clutching relation to the pulley 442 by connections with a cam 542 mounted to turn freely upon the sleeve 438 and geared to said sleeve to be turned once for two rotations of said sleeve and therefore once for two rotations of the pulley 442 by a train of gears 544, 546, 548, the gear 548 meshing with the gear 436.

The clutch operating connections to the cam 542 comprise a lever 550, of the second class, fulcrumed at 552 upon the machine frame, this lever being forked and having in each of its fork members a slot 554 which receives one of the trunnions 556 upon a ring 558 confined between the threaded ring 540 and a shoulder of the sleeve 528, the ring 558 being adapted to turn freely upon the sleeve 528. A two-part bell-crank lever arranged to turn about a vertical stud or shaft 560 carries upon one arm 562 a cam roll 564 which bears against the cam 542. The other arm 566 of the two-part bell-crank lever is connected by a vertically pivoted link 568 with a second link 570 which turns about a horizontal pivot upon the upper end of the lever 550. When the two parts 572 and 574 of the bell-crank lever are connected, as

shown in Fig. 5, the engagement of the high part of the cam 542 with the cam roll 564 causes the clutch member 526 to be moved out of clutching relation to the pulley 442.

The connection between the two parts 572 and 574 of the two-part bell-crank lever is so constructed and arranged that these parts may be disconnected so that the spring 538 may be permitted to move the clutch member 526 into clutching relation to the pulley 442 while the cam roll 564 is still in engagement with the high part of the cam 542. The illustrated connection between the two parts 572 and 574 of the two-part bell-crank lever comprises a pin 576 carried by the lower part 574 of the two-part bell-crank lever, this pin being arranged to slide through an opening in the bottom 578 of a socket in the part 572 and being normally held in its highest position by a spring 580 confined between the bottom of the said socket and a collar upon said pin, whereby the projecting upper end of the pin is normally maintained in a hole 584 in the upper part 572 of the two-part bell-crank lever.

Clamped to the end of the pin 576 which projects below the bottom 578 of the socket in the member 574 is a sleeve 586 provided with a lug 588 over which a hook 590 pivoted at 591 upon a bracket 592 clamped upon a rod 593 is normally hooked, the hook 590 being drawn toward its operative relation to the lug 588 by a spring 594 and being limited in its movement in this direction by a lug 595 upon the bracket 592, whereby a rounded portion 596 upon the upper end of said hook 590 is brought into such relation to the path of travel of the hook with the rod 593 that as said hook engages the lug 588 on the return movement of the rod 593 it will slip over the said lug 588. It will be noted that the movement of the bell-crank is in such a direction that it moves the lug 588 out of engagement with the hook 590 when the clutch member 526 is moved into clutching relation to the pulley 442.

The rod 593 is arranged to move vertically in guides 598, 600 and is provided with a vertical groove 602 into which extends a screw 604 to keep the rod from turning about its longitudinal axis. A spring 606 confined between the lower guide 600 and the bracket 592 tends to keep the rod 593 in its uppermost position. The rod 593 may be depressed to move the bracket 592 downwardly by means of connections to a treadle (not shown) in the base of the machine, these connections comprising a rod 610 pivotally connected to the treadle between its ends and having at its upper end a yoke 612 which receives trunnions carried by a sleeve 614 confined upon the rod 593 by a collar 616. Depression of the rod 610 causes the sleeve 614 to pull downwardly

on the collar 616, thereby depressing the rod 593 against the spring 606. As the rod 593 is depressed it carries down the bracket 592 and the hook 590 bearing upon 5 the lug 588 pulls the pin 576 out of the hole 584 in the part 572 of the two-part bell-crank lever, thereby permitting the spring 538 to move the clutch member 526 into engagement with the pulley 442. As 10 the sleeve 438 begins to turn with the pulley 442, the cam 542 rotates so that the cam roll 564 bears upon the lower part of the cam, that is, the part nearer the shaft 440, thereby permitting the part 574 of the bell- 15 crank to be swung back against the tension of a spring 618 into position to bring the pin 576 again beneath the hole 584 in the part 572.

The means for operating the sole laying 20 mechanism automatically comprises an arm 620 carried upon a hub 621 loosely mounted upon a horizontal rock-shaft 622, the hub 621 being provided with a tooth 623 adapted to be engaged by a tooth 624 upon a sleeve 25 625 keyed upon the shaft 622 whereby it may slide longitudinally upon said shaft to bring its tooth 624 into and out of engagement with the tooth 623 upon the hub 621. The arm 620 is arranged to engage 30 a ledge 626 formed upon the bracket 592. The rock-shaft 622 is rocked to cause the arm 620 to depress the bracket 592 and with it the hook 590 by connections to the gear wheel 524 comprising an arm 627 clamped 35 at one end upon the shaft 622 and having at its outer end a cam roll which enters a cam groove 628 in the gear wheel 524.

In order that the nailing mechanism may 40 be easily turned over by hand without actuating the sole laying mechanism, means is provided for interrupting the operating connections between the nailing mechanism and the sole laying mechanism, this means serving also to remove the brake 458 from 45 the brake surface 456 upon the clutch member 444. The illustrated means comprises a rod 629 (Fig. 4) connected to the brake member 458 and upon which is confined, between a collar 630 and a cam face 632 50 formed upon the bearing in the frame for said rod, a cam sleeve 631 provided with a handle 633 which, as it is turned upon said rod 629, either moves said rod longitudinally to remove the brake 458 from the 55 brake surface 456 upon the clutch surface 444, or permits said brake to be moved back into its operative braking position by a spring 634, bearing at one end against said brake and at its other end against the bottom of a socket in the machine frame. Clamped upon the brake 458 is an arm 636 60 which is connected by a rod 637 to a yoke 638 receiving trunnions upon a ring 639 confined by collars upon the sleeve 625. When

the cam sleeve 631 is turned in a direction 65 to move the brake 458 out of engagement with the brake surface 456, the rod 637 will be moved in a direction to cause the tooth 624 on the sleeve 625 to be moved out of engagement with the tooth 623 on the hub 70 621 whereby when the rock-shaft 622 is turned the arm 620 will not be turned with said rock-shaft and the sole laying mechanism will not be clutched to the pulley 442.

The operation of the parts of the several 75 mechanisms has been sufficiently set forth in detail in the foregoing description of the several mechanisms. In the use of the machine the operator usually or commonly first jacks the shoe thus, as heretofore explained, 80 pressing the shoe into operative engagement with the heel part laying pad. When the heel portion of the shoe has been laid the operator starts the machine by depressing the treadle 490 which, through connections 85 492, link 480 and lever 464, causes the clutch member 442 to engage the continuously rotating pulley 442 whereupon the heel seat end securing gang of fastenings are inserted. During the insertion of the heel seat fastenings 90 the forepart sole laying pad moves into position through its connections with the eccentric 418 on the shaft 420 to lay the forepart of the sole. It will be observed that the heel seat fastenings are all inserted during the first complete revolution of the cam shaft. To effect further revolutions of the 95 said shaft to return the forepart sole laying pad to its inoperative position after the completion of the forepart laying operation, 100 usually a treadle (not shown) is depressed thereby lowering the rod 610 which pulls downwardly on the collar 616 and releases the pin 576 to enable the clutch member 526 to move into operative relation to the pulley 442. It will be noted, however, that if desired the forepart pad can be returned to its inoperative position by manipulation of the hand wheel which is integral with the 105 clutch member 526, the stop 519 at this time 110 being arranged in the path of an adjustable stop 523 upon the lever 464 to prevent engagement of the clutch member 444 with the pulley 442. The described construction and arrangement whereby both manually operated and power operated means for operating the sole laying pad are provided have the advantage of permitting the operator to examine the shoe while it is in the 115 forepart sole laying means without operating the fastening inserting mechanism to insure proper operation of the sole laying means. Furthermore, it will be noted that after the forepart sole laying pad has been brought into its operative sole laying position 120 the operator may subject the sole of the shoe to the forepart sole laying pressure for any length of time which may be desirable, 125

since the illustrated construction and arrangement require a further actuation of the power driven mechanism by a separate treadle (not shown) or manipulation of the hand wheel to return the forepart sole laying pad to its inoperative position. If desired, the invention may be practised by employing pairs of twin machines in which case the operator may advantageously nail and lay the heel seat of one shoe and then, after laying the forepart of that shoe, leave the shoe in the forepart sole laying means while he similarly operates the other machine upon a second shoe, thereby insuring that the forepart of each shoe is allowed to set under sole laying pressure a sufficient length of time.

Having fully described my invention, I claim as new and desire to secure by United States Letters Patent:

1. A machine of the class described having, in combination, means for laying the heel seat end of a sole, means for inserting fastenings to attach the heel seat end of said sole while in said laying means, and other means acting automatically after the attaching operation for laying the remainder of the sole.

2. A machine of the class described having, in combination, means for attaching the heel seat end of a sole constructed to insert at one operation all of the fastenings required to attach the heel seat, and means for laying the remainder of the sole while the shoe is in position to be operated upon by said first mentioned means.

3. A machine of the class described having, in combination, means for inserting fastenings to attach the heel seat end of a sole to the insole and upper, and means acting automatically after the heel seat securing operation for laying the forepart of the sole.

4. In a fastening inserting machine, the combination with a nail block provided with a plurality of nail receiving openings and shaped upon its under side to fit the heel seat end of a shoe, of means for pressing the shoe and outsole against the under side of said nail block to lay the heel seat end of the outsole, other means operating to lay the remainder of the sole, and drivers operating through the nail receiving openings in the nail block to drive heel seat attaching nails into said sole while it is being laid.

5. A machine of the class described having, in combination, means for laying the heel seat end of a sole, and other means for laying the remainder of said sole, together with means for inserting fastenings in one of said sole parts after it is laid, one of said sole laying means being arranged to operate after the other of said sole laying means.

6. A machine of the class described hav-

ing, in combination, means for laying the heel seat end of a sole, means for inserting fastenings to attach the heel seat end of said sole, and means for laying the forepart of the sole, one of said laying means being arranged to operate after the other of said laying means.

7. A machine of the class described having, in combination, means for laying the heel seat end of a sole, means for inserting fastenings to attach the heel seat end of said sole, and other means for laying the forepart of the sole constructed and arranged to be held out of operative relation to the shoe until the heel seat end of the sole has been laid.

8. A machine of the class described having, in combination, means for laying a part of a sole and other means for laying the remainder of the sole, together with means for inserting fastenings in one part of the sole, one of said sole laying means being arranged to be operated after the attaching operation.

9. A machine of the class described having, in combination, means for laying a part of a sole, means for inserting fastenings in that part of the sole, and other means operating after the inserting operation to lay the remainder of the sole.

10. A machine of the class described having, in combination, means for laying one part of a sole, other means for laying the remainder of the sole after the sole laying operation of said first named means, and means for inserting fastenings in said first named part of the sole.

11. A machine of the class described having, in combination, means for laying the heel seat end of a sole, means for laying the forepart of the sole, and means for attaching the heel seat end of the sole constructed and arranged to be operated after the completion of the sole laying operations.

12. A machine of the class described having, in combination, means for laying one part of a sole, and other means for subsequently laying the remainder of the sole, together with means for inserting fastenings in one of said parts of the sole after that part of the sole has been laid.

13. A machine of the class described having, in combination, means for laying the heel seat end of a sole, means for inserting fastenings to attach the heel seat end of the sole to the shoe, and other means for laying the forepart of the sole constructed and arranged to permit laying the forepart of the sole after the heel end of the sole has been laid and attached to the shoe.

14. A machine of the class described having, in combination, means for inserting fastenings in one part of a sole, and sole laying mechanism comprising means for laying

that part of the sole while the sole is in position to be operated upon by the fastening inserting means and other means for laying the remainder of the sole.

5 15. A machine of the class described having, in combination, means for laying the heel seat end of a sole, other means for laying the forepart of the sole, and means for inserting fastenings to attach the heel seat 70 end of the sole while the sole is in the laying means.

16. A machine of the class described having, in combination, means for laying one part of a sole, means for inserting fastenings 15 in that part of a sole while the sole is in said laying means, and other means for laying the remainder of the sole.

17. A machine of the class described having, in combination, means for laying one 20 part of a sole, means for laying the remainder of the sole, and means for inserting fastenings in one of said parts of the sole while the sole is held in the sole laying means.

18. A machine of the class described having, in combination, means for laying the heel seat end of a sole, means for inserting fastenings to attach the said heel seat end 25 of the sole, and other means operating to lay the remainder of the sole while the shoe is in position to be operated upon by the fastening inserting means.

19. A machine of the class described having, in combination, means for laying the heel seat end of a sole, means for attaching 30 the heel seat end of the sole, and other means operating to lay the forepart of the sole while the sole is held in said heel seat laying means.

20. A machine of the class described having, in combination, means for laying part 40 of a sole and for inserting fastenings in said part of the sole, and means for laying the remainder of the sole while the shoe is in position to be operated upon by said first named 45 means.

21. A machine of the class described having, in combination, means for laying and for attaching the heel seat end of a sole, and means for laying the remainder of the sole 50 while the shoe is in position to be operated upon by said first named means.

22. In a fastening inserting machine, means for laying part of a sole and for inserting fastenings therein, other sole laying 55 means, and means for bringing the last mentioned sole laying means into operative sole laying position after the attaching operation is completed.

23. In a machine of the class described, 60 means for inserting fastenings in a sole, sole laying means, and means for automatically bringing said sole laying means into operative sole laying position after the inserting operation.

65 24. In a fastening inserting machine,

means for inserting fastenings in a sole, sole laying means, and means for bringing said sole laying means into operative sole laying position after the inserting operation is completed, together with means for bringing 70 said sole laying means again into inoperative position after the sole has been allowed to set to shape.

25. A machine of the class described having, in combination, means for inserting fastenings in a part of a sole, means for laying the remainder of the sole automatically 75 after the inserting operation, and manually actuated means to move said sole laying means into inoperative position after the 80 sole has been allowed to set to shape.

26. In a machine of the class described, means for inserting fastenings in a sole, sole laying means, and means for automatically bringing said sole laying means into 85 operative sole laying position after the inserting operation, together with manually actuated means for bringing said sole laying means into inoperative position after the sole has been allowed to set to shape. 90

27. In a machine of the class described, means for inserting fastenings in a sole, and sole laying mechanism constructed and arranged to be manually actuated to be brought into operative sole laying position 95 before the attaching operation, together with means for automatically moving said sole laying mechanism out of operative position after the inserting operation is completed. 100

28. In a machine of the class described, means for inserting fastenings in a sole, sole laying means constructed and arranged to be brought into operative sole laying position before the attaching operation begins, 105 and means for automatically moving said sole laying means out of operative position after the attaching operation is completed.

29. A machine of the class described having, in combination, means for inserting fastenings to attach the heel seat end of a sole to the insole and upper, means for laying the forepart of the sole, manually actuated means for moving said sole laying means into operative relation to the forepart of the sole before the operation of said fastening inserting means, and automatically actuated means for returning said sole laying means to inoperative position after the fastening inserting operation is completed. 115 120

30. A machine of the class described having, in combination, means for inserting fastenings to attach the heel seat end of a sole to an insole and upper, means for laying 125 the forepart of the sole, automatically actuated means for moving said sole laying means into operative relation to the forepart of the sole before the operation of said fastening inserting means, and manu- 130

ally actuated means for returning said sole laying means to inoperative position after the fastening inserting operation is completed.

5. 31. In a machine of the class described, in combination, sole laying means constructed and arranged to permit first laying one part of a sole and then separately laying the remainder of the sole, together with 10 means for inserting fastenings in one of said parts of the sole after the sole laying operation on that part of the sole.

32. A machine of the class described having, in combination, means for laying a part 15 of a sole, means for inserting fastenings in that part of the sole, and other means for laying the remainder of the sole.

33. A machine of the class described having, in combination, means for laying a part 20 of a sole, means for inserting fastenings in said sole, and other means operating to lay the remainder of the sole.

34. A machine of the class described having, in combination, means for laying the 25 heel seat end of a sole, means for inserting fastenings to attach the said heel seat end of the sole, and other means for laying the remainder of the sole.

35. A machine of the class described having, in combination, means for laying the 30 heel seat end of the sole, and other means for laying the remainder of the said sole, together with means for inserting fastenings in one part of said sole after that part 35 of the sole has been laid.

36. A machine of the class described having, in combination, means for laying one part of a sole, other means operated automatically to lay the remainder of the sole, 40 and means for inserting fastenings in one of said parts of the sole after that part of the sole has been laid.

37. A machine of the class described having, in combination, means for inserting 45 fastenings in one part of a sole, and means for laying the remainder of the sole automatically after the attaching operation.

38. A machine of the class described having, in combination, means for laying one 50 part of a sole, other means for laying the remainder of the sole, manual means for operating one of said sole laying means, and means for inserting fastenings in one of said parts of the sole after that part of the sole 55 has been laid.

39. A machine of the class described having, in combination, means for laying one part of a sole, other means for laying the remainder of the sole, and means for inserting fastenings in one of said sole parts 60 constructed and arranged to insert at one operation all of the fastenings desired to be inserted in that part of the sole.

40. A machine of the class described having, in combination, means for laying the

heel seat end of a sole, means for attaching the heel seat end of the sole constructed and arranged to insert at one operation all of the fastenings required to attach the said heel seat end of the sole, and other means 70 for thereafter laying the forepart of the sole.

41. A machine of the class described having, in combination, means for laying the heel seat end of a sole, other means for laying the forepart of the sole, and means for inserting fastenings in one of said parts of the sole constructed and arranged to insert at one operation all of the fastenings desired to be inserted in that part of the sole. 80

42. A machine of the class described having, in combination, means for laying the heel seat end of a sole, other means for laying the forepart of said sole, and means for attaching the heel seat end of said sole constructed and arranged to insert at one operation all of the fastenings required to attach the heel seat end of said sole. 85

43. A machine of the class described having, in combination, a heel pad adapted to 90 lay the heel seat end of an outsole upon the shoe bottom, fastening inserting mechanism constructed and arranged to insert a plurality of fastenings to attach the heel seat end of the outsole to the shoe after it has been laid, a forepart pad shaped to conform the forepart of the outsole to the shoe bottom, and means for causing the forepart pad to lay the forepart of the outsole while the outsole is held by the heel pad. 100

44. In a fastening inserting machine, the combination with a nail block shaped to fit one part of a shoe sole, means for pressing the shoe and outsole against said nail block to lay that part of the sole, other means for laying the remainder of the sole, and nail driving means operating through said nail block to drive nails into said sole. 105

45. In a fastening inserting machine, the combination with a nail block shaped to fit the heel seat end of a shoe, of means for pressing the shoe and outsole against the nail block to lay the heel seat end of the outsole, other means operating to lay the remainder of the sole, and nail driving means operating through said nail block. 110

46. In a fastening inserting machine, the combination with a nail block shaped to fit the heel seat end of a shoe, of means for pressing the shoe and outsole against the nail block to lay the heel seat end of the outsole, a pad for laying the forepart of the sole, means for pressing the forepart laying pad against the sole, and nail driving means operating through said nail block 115 to drive heel seat attaching nails into said sole. 120

47. In a fastening inserting machine, the combination with a nail block provided with a plurality of nail receiving openings and 125

shaped upon its under side to fit a part of a shoe sole, of means for pressing the shoe and sole against the under side of said nail block to lay that part of the sole, nail drivers 5 operating through the nail receiving openings in the nail block to insert fastenings in said part of the sole, and other means for laying the remainder of the sole.

48. In a fastening inserting machine, the 10 combination with a nail block provided with a plurality of nail receiving openings and shaped upon its under side to fit the heel seat end of the shoe, of means for pressing the shoe and outsole against the under side 15 of said nail block to lay the heel seat end of the outsole, nail drivers operating through the nail receiving openings in the nail block to drive heel seat attaching nails into said sole, and other means for laying the remainder 20 of the sole.

49. In a fastening inserting machine, the combination of a nail block shaped upon its under side to conform to the bottom of the heel seat end of a shoe and having a plurality 25 of fastening receiving openings, means for forcing the heel seat end of a shoe and an outsole against the under side of the nail block to lay the heel seat end of the outsole on the shoe bottom, fastening inserting 30 means operating through the openings in the nail block to attach the heel seat end of the outsole to the shoe, a pad adapted to conform the forepart of the outsole to the shoe bottom, and means for moving the 35 pad into engagement with the forepart of the outsole.

50. A machine of the class described having, in combination, means for laying the heel seat end of a sole, means for laying the remainder 40 of said sole, and manually controlled means for causing the sole laying operation of the last-mentioned means.

51. In a machine of the class described, in combination, means for laying the heel seat end of a sole, means for laying the remainder of said sole, and manually operated means for causing the sole laying operation of the last-mentioned means, said first-mentioned means consisting of two clamping 45 members which remain stationary to hold the sole during the operation of the other sole laying means.

52. In a machine of the class described, in combination, means for laying one part 55 of a sole, and independently actuated means for thereafter laying the remainder of the sole while the sole is held by said first named means.

53. In a machine of the class described, in combination, means for laying the heel seat end of a sole, and independently actuated means for laying the remainder of said sole, one of said means being arranged to be operated after the other of said means while

the sole is being operated upon by said other means.

54. In a machine of the class described, means for automatically laying one part of a sole, in combination with other means under the control of the operative for laying 70 the remainder of said sole in the same cycle of operations of the machine.

55. In a machine of the class described, in combination, sole laying means constructed and arranged to be operated first 75 to lay one part of a sole and then to lay the remainder of the sole, together with operating mechanism for said means constructed and arranged to be under the control of the operative so that one part of the sole 80 may be laid and then the other part after an interval determined by the operative.

56. A machine of the class described having, in combination, means for laying the heel seat end of a sole, and other means 85 for laying the forepart of the sole, said forepart sole laying means being constructed and arranged to be held out of operative relation to the shoe until after the heel seat end of the sole has been laid 90 and then to be actuated at the will of the operative.

57. In a machine of the class described, in combination, means for laying the heel seat end of a sole, means for laying the remainder 95 of said sole, and manually controlled means for causing the application of one of said sole laying means to the sole before the other is applied.

58. In a machine of the class described, 100 means for laying the heel seat end of a sole, means for laying the remainder of the sole, manually operated means for applying one of said laying means to the sole, and power operated means for removing from the sole the laying means which was applied by the manually operated means.

59. In a machine of the class described, a two-part sole laying pad constructed and arranged to form a continuous sole engaging surface when both parts of said sole laying pad are in operative position, and means for operating first one part of said pad and then, at the will of the operative, the other part of said pad to lay two parts 110 of the sole successively.

60. In a machine of the class described, in combination, a heel seat laying pad and a forepart laying pad, means for holding the forepart pad out of operative position until the operation of the heel seat pad has been completed and means under the control of the operative for causing the operation of the forepart laying pad.

61. In a machine of the class described, 125 in combination, sole laying means comprising a heel seat laying pad and a forepart laying pad, a work support movable to press

the sole against the heel seat pad to lay the heel seat end of the sole, and means under the control of the operative for thereafter moving the forepart pad to lay the forepart of the sole while the work support holds the heel seat end of the sole against the heel seat pad.

62. A machine of the class described having, in combination, means for laying part 10 of a sole and for inserting fastenings in

said part, and means for laying the remainder of the sole.

63. A machine of the class described having, in combination, means for laying and for attaching the heel seat end of a sole, ¹⁵ and means for laying the remainder of the sole at the will of the operator.

In testimony whereof I have signed my name to this specification.

PERLEY R. GLASS.
